UNITED STATES PATENT OFFICE

168,439

SWING

John S. Dishesare, Nevada City, Calif.

Application August 12, 1952, Serial No. 20,974

Term of patent 14 years

(Cl. D34—5)

To all whom it may concern:

Be it known that I, John S. Dishesare, a citizen of Italy, residing at Nevada City, in the county of Nevada and State of California, have invented a new, original, and ornamental Design for a Swing, of which the following is a specification, reference being had to the accompanying drawing, forming part thereof.

Fig. 1 is a side elevation of a swing showing my new design, both sides appearing identical.

Fig. 2 is a front elevation with the rear elevation appearing identical.

Fig. 3 is a top plan view.

Fig. 4 is a half bottom view with the other half being symmetrical about the center line.

I claim:

The ornamental design for a swing, as shown and described.

JOHN S. DICHESARE.
